(57) **CLAIM**

The ornamental design for a soil sensor as shown and described.

DESCRIPTION

FIG. 1 is a perspective view of a soil sensor.

FIG. 2 is a top view of the soil sensor of FIG. 1.

FIG. 3 is a front side view of the soil sensor of FIG. 1. The rear side of the soil sensor has the same appearance as FIG. 3.

FIG. 4 is a right side view of the soil sensor of FIG. 1. The left side of the soil sensor has the same appearance as FIG. 4; and,

FIG. 5 is a bottom view of the soil sensor of FIG. 1. The broken lines in the figures are shown for the purpose of illustrating portions of the soil sensor and form no part of the claimed design.
